(57) **CLAIM**

The ornamental design for a tire for automobile, as shown and described.

DESCRIPTION

The patent or application file contains at least one drawing executed in color. Copies of this patent or patent application publication with color drawing(s) will be provided by the office upon request and payment of the necessary fee.

FIG. 1 is a front left perspective view of a tire for automobile showing my new design;

FIG. 2 is a front view thereof, a rear view being a mirror image thereof; and,

FIG. 3 is right side view thereof, a left side view being the same.

The top view and the bottom view are the same as the front view.

In the drawings, the broken lines defining the sidewall, inner bead and the tire shoulder between the outermost tread groove and the unclaimed sidewall depict environmental subject matter and the outer boundary that forms no part of the claimed design.

(*) Notice: This patent is subject to a terminal disclaimer.
